COMBINED PAD AND PENCIL HOLDER FOR A TELEPHONE

Anthony Victor Farina, 227 Michigan St.,
New Kensington, Pa.

Filed Feb. 25, 1960, Ser. No. 59,517

Term of patent 14 years

(Cl. D26—14)

Fig.1.

Fig.2.

Fig.3.

Fig.4.

Fig. 1 is a top view of a combined pad and pencil holder for a telephone, showing my new design.

Fig. 2 is a side view thereof wherein a pad of paper is shown in broken lines in the pad holder for illustrative purposes only;

Fig. 3 is a top perspective view thereof; and

Fig. 4 is a bottom perspective view, thereof.

The broken line showings of a telephone in Figs. 1 and 2 and of a pencil in Fig. 2 are for illustrative purposes only.

I claim:

The ornamental design for a combined pad and pencil holder for a telephone, substantially as shown and described.
